UNITED STATES PATENT OFFICE.

JOHN BROWN HARRIS, OF NASHVILLE, TENNESSEE, ASSIGNOR TO EDGAR G. HARRIS, OF NASHVILLE, TENNESSEE.

SMOKE-CONSUMING FURNACE.

No. 880,380.

Specification of Letters Patent.

Patented Feb. 25, 1908.

Application filed April 20, 1907. Serial No. 369,247.

To all whom it may concern:

Be it known that I, JOHN BROWN HARRIS, a citizen of the United States, and a resident of Nashville, in the county of Davidson and State of Tennessee, have invented a new and Improved Smoke - Consuming Furnace, of which the following is a full, clear, and exact description.

The invention relates to smoke consuming furnaces such as shown and described in the Letters Patent of the United States, No. 754,999 and No. 784,324 granted to me on March 22, 1904 and March 7, 1905, respectively.

The object of the present invention is to provide a new and improved smoke consuming furnace arranged to produce a high heat and complete combustion by the burning of a mixture of air and producer or water gas, the latter being obtained by superheating the steam to dissociation and passing the dissociated oxygen and hydrogen in fine jets into the products of combustion arising from the burning fuel in the fire box, the air being highly heated before entering the fire box and reaching the producer gas.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a longitudinal sectional elevation of the improvement, as arranged in a return tubular boiler; Fig. 2 is an enlarged transverse section of the same on the line 2—2 of Fig. 1; Fig. 3 is a sectional plan view of the same on the line 3—3 of Fig. 2; Fig. 4 is a sectional side elevation of the improvement applied to a water tube boiler of the Heine type; Fig. 5 is a like view of the improvement as applied to a water tube boiler of the Babcock & Wilcox type; Fig. 6 is a transverse section of the same on the line 6—6 of Fig. 5, and Fig. 7 is a sectional side elevation of the improvement as arranged in an upright water tube boiler.

As illustrated in Figs. 1, 2 and 3, the boiler A is set in the usual manner in a brick-work B containing a fire box C having a grate D, below which is arranged an ash pit E, access being had to the said fire box C and ash pit

E by suitable doors C' and E'. At the rear end of the fire box C is arranged a bridge wall F having a checker-work top F', behind which is the combustion chamber G leading to the rear end of the boiler A, to direct the heated gases into and through the flues of the boiler A in a forward direction, so that the gases finally pass into the stack A'.

In the front upper portion of the fire box C are arranged air chambers H and H' formed by spaced concentric arches H² and H³ extending from the side walls of the brick-work B, the top of the upper arch H² being spaced from the under side of the boiler A, to leave the latter unobstructed at this point and thus maintain a full heating surface of the boiler throughout the length thereof. The lower arch H³ extends above the door C' so as not to obstruct the entrance to the fire box C. A longitudinally extending partition H⁴ is arranged between the arches H² and H³, to form the two chambers H and H', one alongside the other, and the outer ends of the said chambers H and H' are connected by air ducts I and I' with the ash pit E, the said ducts extending through the side walls of the brick-work B, as plainly indicated in Fig. 2. Thus air from the ash pit E can pass up through the ducts I and I' into the chambers H and H', the air being heated in its passage by passing through the heated ducts contained in the side walls of the brick-work B, and by passing into the chambers H and H' is further heated by the red hot fire brick walls of said air chambers. The entrance ends to the ducts I and I' are provided with suitable dampers I², to permit of controlling the amount of air passing up into the chambers H and H'.

Within the air chambers H and H' are arranged the steam dissociating blowers J and J', each preferably in the form of a flat casing of cast iron or the like, and provided at its bottom with lugs J² resting on the top surface of the arch H³, so as to support each dissociating blower J and J' freely within the corresponding chamber H or H', to permit the air to pass completely around the said dissociating blower J or J'. The front ends of the steam dissociating blowers J and J' are connected by pipes K having valves K', with the steam dome A² of the boiler A, so as to allow the steam to pass into the said dissociating blowers, with a view to heat the steam to such an extent that it readily dis-

sociates into its constituents hydrogen and oxygen, the dissociated steam passing out of the blowers J and J' at their rear ends through jets J³ located in the outlets H⁵ of the chambers H and H', as plainly indicated in Fig. 1. The jets J³ are formed in such a manner as to direct the dissociated steam through the products of combustion arising from the burning fuel on the grate D and also to direct the said dissociated steam towards a gas bench L arranged in the rear of the grate D at the front side of the bridge wall F.

By reference to Fig. 1, it will be seen that the inner end of the upper arch H² projects a distance beyond the inner end of the lower arch H³, so that the heated air passing from either chamber H or H' to the outlet H⁵ readily commingles with the dissociated steam issuing from the jets J³ so as to be forced with the dissociated steam in the direction of the gas bench L.

In order to prevent the mixture of air and gas striking the side walls of the fire box C, the inner ends of the air chambers H and H' are provided at their sides with fire bricks H⁶ leading to the outer side of the corresponding steam dissociating blowers J and J', as will be readily understood by reference to Fig. 3. Now by the arrangement described a large heating area is provided in each blower J and J', to insure a dissociation of the elements of the steam, and the dissociated steam in passing through the products of combustion arising from the burning fuel in the fire box C causes a production of producer or water gas, and the heated air coming in contact with this producer or water gas causes a burning thereof, at the same time developing a high heat and utilizing the burning fuel to the fullest advantage by insuring complete combustion thereof. The flame in passing through the checker work top F' is comminuted or chopped up into small, thin tongues, and consequently a perfect combustion is obtained.

By reference to Fig. 1 it will be noticed that the inner or jet end of the dissociating blower J or J' is set back slightly from the inner end of the lower arch H³, so as to prevent exposure of the jet end of the blower to the products of combustion arising from the burning fuel in the fire box C.

The jets J³ are preferably arranged in fan shape in a transverse direction, so as to spread the dissociated steam in the fire box C, to insure a complete commingling of the dissociated steam with the products of combustion arising from the burning fuel. By directing the dissociated steam downward and rearward towards the gas bench L, the mixture after impact with the gas bench L is deflected upward by the gas bench, to insure further intimate commingling of the constituent parts of the gas. It is understood that as the gas bench L tends to send the

burning gases in an upward direction, the said gases are prevented from going downward to and through the rear end of the grate and burning the same.

Although I have shown and above described the improvement in relation to a horizontal tubular boiler, it is evident that the device is readily applicable to furnaces of various types. For instance, as shown in Fig. 4, the device is applied to a water tube boiler N of the Heine type, and as shown in Figs. 5 and 6, to a similar boiler O of the Babcock & Wilcox type, and in Fig. 7 is shown a vertical water tube or tubular boiler P provided with the improvement.

In the forms illustrated in Figs. 4, 5 and 6, the steam dissociating blowers J, J' fit with their upper faces against the under side of the top arch H², but otherwise the construction of the device is the same as above described, in reference to Figs. 1, 2 and 3.

Although I have shown the intake of the air duct I, I' as coming from the ash pit E, it is evident that I do not limit myself to this arrangement, as the air ducts may be otherwise arranged, as, for instance, shown in my last patent above referred to.

Having thus described my invention, I claim as new and desire to secure by Letters Patent:

1. A furnace comprising a fire box and a plurality of concentric spaced arches at the front of the fire box, a dividing wall arranged longitudinally between the arches and dividing the space into two compartments, said fire box being provided with air ducts leading from the ash pit to the compartments and a disassociator in each compartment, said disassociator comprising a casing of relatively great length and of relatively small depth and being provided with a steam inlet pipe, and a series of outlets at its rear end, said outlets being directed downward and backward, whereby to direct the disassociated elements of the steam through the burning gases of the fuel, said fire box having a gas bench against which said products are directed, said bench being inclined forwardly and downwardly to deflect said products upwardly through the burning gases, said lower arch being inclined downwardly at its rear edge, and the upper arch projecting beyond said inclined portion for the purpose set forth.

2. A furnace comprising a fire box, a plurality of concentric spaced arches at the front of the fire box, a dividing wall arranged longitudinally between the arches and dividing the space into two compartments, said fire box being provided with air ducts leading from the ash pit to the compartments and a disassociator in each compartment, said disassociator comprising a casing of relatively great length and breadth and of relatively small depth, and being pro-

vided with a steam inlet pipe, and a series of outlets at its rear end, said outlets being directed downward and backward whereby to pass the disassociated elements of the steam 5 through the burning gases of the fuel, said fire box having a gas bench against which the said products are directed, said bench being inclined forwardly and downwardly, whereby to deflect said disassociated elements upwardly through the burning gases for the purpose set forth.

3. A furnace comprising a fire box, a plurality of concentric spaced arches at the front thereof said fire box being provided 15 with an air duct leading from the ash pit to the space between the arches, a disassociator between the arches, said disassociator comprising a casing of relatively great length and of relatively small depth and being provided

with a steam inlet pipe, and a series of outlets at its rear end, said outlets being directed downward and backward whereby to pass the disassociated elements of the steam 20 through the burning gases of the fuel, said fire box having a gas bench against which the said products are directed, said bench being inclined forwardly and downwardly whereby to deflect said disassociated elements upwardly through the burning gases for the purpose set forth.

In testimony whereof I have signed my name to this specification in the presence of two subscribing witnesses.

JOHN BROWN HARRIS.
